UNITED STATES PATENT OFFICE.

WENDELL A. ADDIS, OF GREENFIELD, MASSACHUSETTS, ASSIGNOR TO GREENFIELD TAP AND DIE CORPORATION, OF GREENFIELD, MASSACHUSETTS, A CORPORATION OF MASSACHUSETTS.

CENTERLESS GRINDING MACHINE.

Application filed June 10, 1924. Serial No. 719,032.

This invention relates to centerless grinding machines, and the principal aim of my invention is to provide a centerless grinding machine with which drills or other cylindrical work may be ground mechanically and automatically to have a uniform back taper of any desired amount within certain limits, and to provide a machine adapted for expeditious quantity production of work having 5 the utmost precision and uniformity. A further object of my invention is to provide a machine of the above character adapted for high speed operation, and adapted to operate efficiently, quickly and with a minimum of 10 expense. A further object of my invention is to provide improved means for automatically feeding successive units of work through the machine. Another object of my invention is to provide improved means for 15 taking each unit of the work against the abrasive wheel so as to be ground in the manner desired. Another object of my invention is to provide means whereby the machine may be adjusted readily and easily for 20 different sizes of work. Other objects of my invention will be in part obvious and in part 25 pointed out hereinafter.

My invention accordingly consists in the features of construction, combinations of elements, and arrangement of parts which will 30 be described hereinafter, and the scope of the application of which will be pointed out in the claims that follow.

In accordance with my invention, the machine includes a work hopper, constantly 35 open for replenishment, adapted to dispense units of work, such as metal bars, rods, or shafts, singly and successively into position for engagement by automatically reciprocating feed means, whereby each unit of work 40 is moved separately and with a continuous forward movement transversely across a grinding means, such as a constantly rotating abrasive wheel, the work during such movement being engaged by positioning 45 means which serve to position and hold the work against the periphery of the grinding wheel to cause the work to be ground. The positioning means include a cam operated 50 work head which receives the work, and the cams gradually and evenly move the work head and the work therein radially away from the grinding wheel as the work is moved endwise through the head by the feed

means, thereby causing the work to be 55 ground with a uniform back taper per unit of length. The work head includes upper and lower supporting members and a rear supporting member or back rest, all relatively adjustable on the head for the proper 60 accommodation of work of different diameters. The back rest for the work preferably includes a roll of abrasive resisting material, and is rotatively adjustable so that different portions of its surface may be presented to the abrasive action of the rotating work being ground, without requiring removal of the back rest from the machine nor the removal of the roll from the rest. The 65 cams of the work head moving and positioning means are interchangeable with other cams, permitting the machine to be adjusted to grind the work to different amounts of back taper per unit of length, or with no 70 back taper. The feed means take the form 75 of a plunger which is continuously reciprocated by means of a rotating drum having forward and return spiral grooves, and which on its forward stroke pushes a unit of work through the work head and then 80 returns to engage and to advance the next unit of work dispensed by the hopper. The cams which drive the movable work head have a synchronized connection with the drum and its driving means. The hopper 85 is made up of a plurality of relatively adjustable parts so as to be fully adjustable for work units of different lengths and diameters.

In order that a clearer understanding of 90 my invention may be had, attention is hereby directed to the accompanying drawings, forming a part of this application and illustrating one possible embodiment of my invention. Referring to the drawings, Fig. 1 95 is a top elevation of a centerless grinding machine embodying my invention, the side members of the hopper being shown in section; Fig. 2 is a side elevation of the same, certain portions being broken away; 100 Fig. 3 is a sectional view taken on the line 2-3 of Fig. 1, looking in the direction of the arrows; Fig. 4 is a sectional view through the work head, and is taken on the line 4-4 of Fig. 3; Fig. 5 is a sectional view taken 105 on the line 5-5 of Fig. 1, looking in the direction of the arrows; and Fig. 6 is an enlarged side view partly in section, and is

taken on the line 6—6 of Fig. 5. Similar reference characters refer to similar parts throughout the several views of the drawings.

- 5 Referring to the drawings, the machine as a whole is secured firmly upon a suitable stand or base 1. The machine includes a main driving shaft 2, journaled in suitable brackets 3 and 4, which are bolted 10 to the base, the shaft being supplied at one end with a drive pulley 5, preferably of the multiple step cone type, whereby the machine may be driven at various speeds in the usual manner by power 15 from any suitable source. A drum 6 is mounted on shaft 2 for rotation therewith, and in its periphery is a right hand spiral groove 7, making two turns around the drum, and a left hand spiral groove 8, making a 20 single turn around the drum. These grooves are mutually continuous at each end of the drum, so that upon every three rotations of the drum a follower 9 engaged in the grooves will be reciprocated, first 25 forwardly for a full stroke during two revolutions of the drum and then rearwardly to initial position during one revolution of the drum. Follower 9 is a part of a cross head 10 which reciprocates on two slides 30 11 secured to the drum shaft brackets 3 and 4, and a plunger or push rod 15 is secured to this cross head for reciprocation therewith. A hopper 12 is adapted to dispense units of work, 13, one by one, to a 35 suitable work centering bed plate 55 directly in advance of push rod 15 when the push rod is in retracted position due to rotation of drum 6. As the head and push rod then move forward again due to continued rotation of the drum, the forward end of the rod engages the rear end of the unit of work and pushes it endwise into and through a work head which serves to position this unit of work in such engagement 40 with the periphery of the rotating abrasive wheel 16 that the work will be ground thereby while the work is being moved through the head and transversely across the wheel by the push rod 15. The work 45 is fully rotatable in the work head by the grinding wheel. The work head includes a main portion 17 upon which are mounted adjustably upper and lower positioning plates, 18 and 19, having oppositely tapered surfaces to center the work, and a back rest 20 which abuts the work on its side opposite the abrasive wheel and holds the work against these tapered surfaces. Plates 18 and 19 are secured to the work head portion 17 by means of screws 21 which extend through slots 22 provided in the plates, permitting the plates to be adjusted vertically on the work head to accommodate the head to work of different diameters. The 55 back rest 20 includes a cylindrical member

23 which directly engages the work and cooperates with plates 18 and 19 to hold it in proper position on the head for engagement against the abrasive wheel 16. Roll 23 is held in position for rotative adjustment by pairs of upper and lower clamping plates 24 and 25, and by a backing block 26 which has a groove 27 in which the roll 23 fits. Block 26 is held on the head by means of screws 28 which extend through 70 slots 29 in the head to permit adjustment of block 26 for different sizes of work and for different amounts of grinding. Such adjustment is effected by means of a slide member 30 which has tapered bosses 31 so engaging cooperating tapered surfaces 32 formed on the rear of member 26. One end 33 of slide 30 extends from the work head and is threaded so that the slide may be adjusted with respect to the head by 75 means of nut 34 and lock nut 35 thereon. It will be readily apparent that by manipulating screws 28 and nut 34, the block 26 and the back roll 23 may be moved and locked in various advanced or retracted 80 positions on the head and with respect to the positioning plates 18 and 19. It is also apparent that the back roll 23 may be revolved readily and easily to bring a fresh portion of its surface against the work, for each pair of clamping plates 24 and 25 is clamped against roll 23 by means of 85 screws 36, and when these screws are loosened the roll 23 may be turned into a new position in which it may be secured by 90 tightening the screws 36. If desired, the roll 23 may be provided at one end with a groove 37 in which a screw driver or other suitable tool may be engaged to turn the roll when the clamping plates are 95 loosened.

The entire work head is pivotally supported on brackets 70 by means of shaft 71 which extends through ears 71' formed on the head portion 17. The rear of the 100 portion 17 is also provided with a pair of projections 38, and immediately behind each of these projections is a cam wheel 39 secured to a shaft 40 which is journaled in brackets 41 fastened on the base 1. Suitable springs, such as 42, constantly and resiliently hold the work head projections 38 against the periphery of the cam wheels 39, so that as the cams 39 revolve the work 105 head is moved toward and from the abrasive wheel 16 in accordance with the configuration of the cam surfaces of the cams. Shaft 40 carries on one end a gear 42 which meshes with a gear 43 secured to the main driving shaft 2, and the ratio between these 110 gears is such that the shaft 40 and the cams 39 carried thereby will be given one complete revolution for every three revolutions of drum 6.

The work hopper 12 is constructed to be 115

fully adjustable for various sizes of drills or other work. There is an angular base casting 44 which is adjustably secured to the machine base 1 by means of screws 45 which 5 penetrate slots 46 in the casting 44. This casting has a threaded boss 47 in which is engaged the threaded end of a screw 48 which is retained for rotation and against longitudinal movement in a bracket 49 secured to base 1. A longitudinal angular frame member 50 is supported for vertical adjustment on the vertical wall of casting 44 by means of screws 51 which extend through slots in member 44. Frame 50 may 10 be adjusted vertically by turning a vertical screw 52 which is threaded into member 44 and which has an annular flange 53 constantly engaged beneath a hook 54 attached to member 50. Member 50 is grooved to accommodate a bar 55 which is provided with a V-shaped slot into which the hopper delivers each unit of work and from which the plunger 15 takes the work into the work head and through the machine. There are 20 two spaced hopper members 56 and 57, each having a vertical channel portion 58 in which the opposite ends of a stack of work units are engaged for successive delivery to the V-bar 55. The hopper brackets 56 and 30 57 are adjustable toward and from each other to accommodate different lengths of drills by being secured to member 50 by means of bolts 59 which have heads 60 engaged in a T-slot 61 in the member 50. A 35 suitable table portion 62 for work units may be associated with the hopper members 56 and 57.

The operation of the machine is as follows:—The main driving shaft is driven 40 constantly at a suitable speed by means of power applied to the pulley 5. After the hopper and the work head have been suitably adjusted for the particular size of work which is to be ground, and after the 45 work head has also been properly adjusted for the particular size of grinding and degree of taper desired to be given to the work by the machine, it is only necessary to continuously feed the work into the hopper, and 50 the work will be delivered automatically and mechanically in successive units from the end of the machine in finished condition. It will be apparent that as the main drive shaft 2 rotates the push rod 15 pushes a unit of 55 work from the hopper, where it has been centered by the V-shaped slot in the member 55, and through the work head between the plates 18 and 19 and between the abrasive wheel 16 and the work rest roll 23. As the 60 rod 15 moves the work into the work head with an even uniform rate, the cam wheels 39 have moved the work head up to its nearest position to the abrasive wheel 16. As the work passes by the face of the abrasive 65 wheels the work head backs away from the

face of the abrasive wheel, due to springs 42 causing the work head to follow the dropping of the surfaces of the cams 39, and due to this retraction of the work relative to the abrasive wheel during grinding and while 70 the work is moved along, the work is caused to be ground with a back taper. As this rod 15 is retracted to initial position to engage another unit of work, the cams 39 advance the work head into its original position. 75 The gearing connections between the drum 6 and the cam shaft 40 result in exact synchronization in movement between the feeding and positioning mechanisms of the machine. Different degrees of back taper may be 80 ground by merely changing the cams 39 for others of different cut. Obviously the cams may be so designed that no taper is given to the work.

As many changes could be made in the 85 above construction, and many different embodiments of the invention could be made without departing from the scope thereof, it is intended that all matter contained in the above description or shown in the accompanying drawings be interpreted as illustrative and not in a limiting sense.

What I claim is:—

1. In a grinding machine of the character described, in combination, a rotary grinding wheel having an abrasive periphery, feed means for moving a unit of work across the periphery of said wheel, and positioning means for moving said work in a radial direction gradually away from said wheel during the entire movement of a predetermined portion of the work across the grinding wheel, whereby said portion of the work is ground with a cylindrical taper, said positioning means holding the work loosely, and the work being rotated by said grinding wheel.
2. In a grinding machine of the character described, in combination, a rotary grinding wheel having an abrasive periphery, feed means for moving a unit of work across the periphery of said wheel, and positioning means for moving said work in a radial direction gradually away from said wheel during the entire movement of a predetermined portion of the work across the grinding wheel, whereby said portion of the work is ground with a cylindrical taper, said feed and positioning means having synchronized movement one with the other, said positioning means holding the work loosely and the work being rotated by said grinding wheel.
3. In a grinding machine of the character described, in combination, a rotary grinding wheel having an abrasive periphery, feed means for moving a unit of work across the periphery of said wheel, and positioning means for moving said work in a radial direction gradually away from said wheel during the entire movement of a predetermined portion of the work across the grinding wheel, whereby said portion of the work is ground with a cylindrical taper, said feed and positioning means holding the work loosely and the work being rotated by said grinding wheel.

portion of the work across the grinding wheel, whereby said portion of the work is ground with a cylindrical taper, said feed means including a reciprocating rod engaging the work endwise, and said positioning means including a reciprocating head engaging the work transversely.

4. In a grinding machine of the character described, in combination, a rotary wheel having an abrasive periphery, movable feed means for moving a unit of work across the periphery of said wheel, and movable positioning means adapted, during such movement of the work, to take the work into varying engagement against said wheel, whereby the work is ground with a taper, said feed means including a reciprocating work advancing member, said positioning means including a reciprocating work holding member, and means for moving said work advancing member and said work holding member in synchronism with each other.

5. In a grinding machine of the character described, in combination, a rotary wheel having an abrasive periphery, movable feed means for moving a unit of work across the periphery of said wheel, and movable positioning means adapted, during such movement of the work, to take the work into varying engagement against said wheel, whereby the work is ground with a taper, said positioning means holding the work for rotation by said grinding wheel during the grinding operation.

6. In a machine of the character described, means for operating upon work fed through the machine, and means for feeding work through the machine, said feed means including a revolving drum having continuous forward and return spiral grooves, a follower in said grooves and a work-engaging plunger connected with said follower for reciprocation by the revolution of said drum.

7. In a machine of the character described, in combination, grinding means, means for feeding work through the machine, and positioning means for taking work fed by said feed means into operative engagement with said grinding means, said positioning means including a movable work accommodating head and associated mechanism, including a cam, determining the position and movement of said head.

8. In a machine of the character described, in combination, grinding means, means for feeding work through the machine, and positioning means for taking work fed by said feed means into operative engagement with said grinding means, said positioning means

including a movable work accommodating head and associated mechanism, including a cam, determining the position and movement of said head, and said work head including a pivotally suspended base, upper and lower work positioning plates adjustably secured to said base, and a back rest adjustably secured to said base, said cam engaging said base.

9. In a machine of the character described, in combination, grinding means, means for feeding work through the machine, and positioning means for taking work fed by said feed means into operative engagement with said grinding means, said positioning means including upper and lower spaced positioning plates and a back rest, cooperating to provide a passage through which a unit of work may be moved endwise with a lateral portion of the work protruding transversely from between said upper and lower plates, and permitting said work to rotate on its longitudinal axis, said back rest including a roll of abrasive resistant material and clamping means maintaining said roll in position on said back rest, said clamping means being adjustable to permit said roll to be adjusted rotatively on said back rest, whereby different portions of its surface may be presented for engagement by work in the head.

10. In a machine of the character described, a hopper adapted to dispense units of work separately for feeding through the machine, said hopper comprising, in combination, a base member mounted for horizontal adjustment on the machine, a horizontal member mounted for vertical adjustment on said base member, and upright work-guiding standards mounted for independent horizontal adjustment on said horizontal member.

11. In a machine of the character described, a hopper adapted to dispense units of work separately for feeding through the machine, said hopper comprising, in combination, a base member mounted for horizontal adjustment on the machine, a horizontal member mounted for vertical adjustment on said base member, and upright work-guiding standards mounted for independent horizontal adjustment on said horizontal member, said horizontal member having a slot positioned to receive work leaving said standards, whereby said work is centered for being fed through the machine.

This specification signed this 6th day of June, 1924.
